UNITED STATES PATENT OFFICE.

GEORGE W. BEAR AND HARLAN P. GARDNER, OF ST. PAUL, MINNESOTA.

DESIGN FOR A FLAG, PENNANT, SIGN, OR ARTICLE OF A SIMILAR NATURE.

52,626.

Specification for Design.

Patented Nov. 12, 1918.

Application filed April 29, 1918. Serial No. 231,554. Term of patent 7 years.

To all whom it may concern:

Be it known that we, GEORGE W. BEAR and HARLAN P. GARDNER, citizens of the United States, residing at St. Paul, county of Ramsey, and State of Minnesota, have invented a new, original, and ornamental Design for a Flag, Pennant, Sign, or Articles of a Similar Nature, of which the following is a specification, reference being had to the accompanying drawings, forming part thereof.

The figure is a plan view of a flag, showing our new design, which illustrates a shrieking

eagle with partly spread wings positioned on a shield having a red border, an inner field of blue which is circumscribed by a white margin, separating the red border from the blue field, and a white star in the blue field.

We claim:

The ornamental design for a flag, pennant, sign or articles of a similar nature, as shown.

GEORGE W. BEAR.
HARLAN P. GARDNER.
